US0D1099165S

(12) **United States Design Patent** (10) **Patent No.:** **US D1,099,165 S**
(45) **Date of Patent:** **** Oct. 21, 2025**

(54) **PORTABLE AIR COMPRESSOR**

(71) Applicant: **ARB Corporation Limited**, Kilsyth (AU)

(72) Inventors: **Daniel Jason Bongard**, Kilsyth (AU); **Andrew Harry Brown**, Kilsyth (AU); **John Desmond Clark**, Kilsyth (AU)

(73) Assignee: **ARB Corporation Limited**, Kilsyth (AU)

(**) Term: **15 Years**

(21) Appl. No.: **29/909,067**

(22) Filed: **Jul. 31, 2023**

(30) **Foreign Application Priority Data**

Feb. 1, 2023	(AU)	202310600
Feb. 1, 2023	(AU)	202310601

(57) **CLAIM**

The ornamental design for a portable air compressor, as shown and described.

DESCRIPTION

FIG. 1 is a top, front, right-side perspective view of a portable air compressor;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The dashed broken lines depict portions of the portable air compressor that form no part of the claimed design.

1 Claim, 7 Drawing Sheets
